UNITED STATES PATENT OFFICE.

JENNIE FRASER MCKENZIE, OF PROVIDENCE, RHODE ISLAND.

DESIGN FOR A TABLE.

SPECIFICATION forming part of Design No. 26,448, dated December 22, 1896.

Application filed November 20, 1896. Serial No. 612,904. Term of patent 7 years.

To all whom it may concern:

Be it known that I, JENNIE FRASER MCKENZIE, a citizen of the United States, residing at Providence, in the county of Providence and State of Rhode Island, have invented and produced a new and original Design for a Table; and I do hereby declare the following to be a full, clear, and exact description of the same, reference being had to the accompanying drawing, forming a part thereof.

The drawing represents in perspective a table made according to my design.

My design for a table consists of two pairs of cross-legs, each leg being made in the form of a shovel. Each pair of legs are crossed at about their middle and are connected together by a bar, to the ends of which the legs are

fastened at the crossing. The top of the table is placed on the legs near their upper ends, which are in the shape of shovel-handles and are made to project above the top of the table. The lower ends of the legs are made broad and flat like the blades of shovels and are curved outward some at their lower edges to make feet to stand on the floor.

25

What I claim is—

The design for a table substantially as shown and described.

In testimony whereof I affix my signature in presence of two witnesses.

JENNIE FRASER MCKENZIE.
